Attorney.

UNITED STATES PATENT OFFICE.

CARL JOHAN ELIGIUS ISAKSSON, OF SPANGA, SWEDEN, ASSIGNOR OF ONE-HALF TO
HUGO THEODORE TILLQUIST, OF STOCKHOLM, SWEDEN.

SPARK PLUG.

Application filed August 13, 1925, Serial No. 50,102, and in Sweden May 22, 1925.

My invention relates to a new and improved spark plug for internal combustion engines, and has for its object to provide a spark plug whose electrodes will automatically keep clean and free from all incrustations, deposit of carbon and the like, that are apt to form on them during the running of the engine. According to the invention this object is attained with very simple means, and without the use of any special rubbing devices or other movable parts, such as valves or the like. The principle, whereupon the invention is based, is to provide the spark plug with a hollow chamber, which communicates with the combustion room of the engine by an opening, channel, pipe or the like, the spark-gap being arranged right in front of and close to the said opening or the like or in the said opening itself in such a way that the electrodes are flushed and cleansed by the currents of gas and air that flow into and out of said hollow chamber during the compression and expansion strokes respectively of the piston.

This principle can of course be carried out in several ways and the structure of the spark plug be modified in a corresponding way.

I have illustrated the invention by way of example in the accompanying drawing, in which—

Figure 1 is a section through a spark plug according to the invention;

Fig. 2 is a plan view of the spark plug in Fig. 1, seen from the combustion chamber; and Fig. 3 is a plan view of a modified spark plug, seen from the combustion chamber.

Similar numerals refer to similar parts throughout the several views.

Referring to Figures 1 and 2, the spark plug comprises in the known way a body 2 of insulating material, which is inserted in a metal casing 1, to be screwed into the cylinder cover. The body 2 is secured to the

casing 1 by means of the threaded cap 3. The body 2 carries in the known way a central electrode 5, which can be connected to the electric circuit by means of a terminal 4. The casing 1 carries the other electrode 6.

The new features of the invention consist therein, that the inner ends of the casing 1 and the body 2 are formed in such a way that a chamber 9 is enclosed between them. This

chamber 9 can be formed in different ways, for instance as shown in Fig. 1 by providing the inner end of the casing 1 with a radial flange 11 directed towards the body 2 and separated from the latter by a narrow circular slot 7. In this flange 11 an opening or channel 8 is made right opposite the spark-gap between the electrodes 5 and 6, which are bent towards each other in a way to bring the spark-gap right in front of the said opening 8.

During the compression stroke of the piston, combustible mixture is pressed through the opening 8 and the slot 7 into the chamber 9, sweeping these passages and the electrodes free from incrustations and the like. At the moment of ignition the pressure in the chamber 9 will also rise to the same height as the pressure in the cylinder itself. As the pressure in the cylinder during the expansion stroke gradually decreases, the compressed mixture in the chamber 9 will continually flow out through the opening 8 and the slot 7, thus again flushing and cleaning the electrodes. Shortly before the end of the expansion stroke, usually after 85-90% of the stroke, the outlet valve begins to open. The pressure in the cylinder then rapidly decreases, which occurs during a disappearingly short time. The stream rises and reaches a considerable strength, subjecting the electrodes to a third thorough cleaning.

During the flowing of gases into or out of the chamber 9, a part of the gases flow through the narrow slot 7. The greatest part of the gases, however, will take the way of the least resistance, that is through the comparatively larger opening 8. The narrow slot 7 is, however, of great importance, as the same affords a way out during the expansion stroke for incrustations, carbon deposits, etc., that now are blown out through the slot but otherwise would tend to accumulate in the chamber 9.

If a spark plug is used, which is provided with several spark-gaps, as shown in Fig. 3, an opening 8 leading to the enclosed chamber should be provided in front of each spark-gap.

I claim:

A spark plug comprising a metal sleeve adapted to be screwed into the cylinder head of an engine, an insulated body positioned

within said sleeve forming a chamber therebetween, a flange formed with the lower end of said metal sleeve having a concentric opening therein through which passes the lower end of said insulated body, electrodes carried by the lower ends of said insulated body and metal sleeve, and said flange having an ec-

centrically positioned opening therein communicating with said chamber and arranged in vertical alignment with said electrodes. 10

In witness whereof I have hereunto set my hand.

CARL JOHAN ELIGIUS ISAKSSON.
